UNITED STATES PATENT OFFICE.

WILLIAM H. B. LAVARACK, OF NORWOOD, NEW JERSEY.

TRACK CIRCUIT.

Application filed January 7, 1925. Serial No. 948.

This invention relates to railway signalling, particularly track circuit signalling and more especially to the track circuit itself.

5 At the present time railway signals in approved practice are controlled by means of what is known as a track circuit. This track circuit is a unit indefinitely repeated. The unit is a section of trackway set off 10 from the rest of the trackway by insulating joints, usually one in each rail at each end of the section. The rails of the section at one end have a source of electrical potential connected across them. At the other 15 end of the section a relay is connected across the track section. Just so long as a pair of wheels connected to a common axle is not on the section the relay is energized by the source of potential sufficiently to maintain 20 its armature in an upper position, or signal circuit closing position. If a pair of wheels connected to a common axle comes upon the section, the relay is shunted, becomes de-energized and its armature falls or opens 25 the signal circuit.

The whole safety of the track circuit depends upon the value in ohms of the shunt made by the wheels and axle. If this resistance is very low the arrangement is effective, if it is very high then the possibility exists that the relay armature will not respond and drop. The possibility that the relay armature will not release or drop or move to open signal circuit position is enhanced by the fact that less current is needed to keep an armature in its upper position than is needed to raise it to that position. In ordinary practice with direct current track relays, the "pick-up" is about 40 seventy milliamperes whereas the "drop away" is about thirty-five milliamperes. A given resistance shunt might well prevent an armature from being lifted but would not cause it to drop or fall.

45 Due to many and well known conditions in actual practice, such for instances as, rusty wheels and rails the train shunt might rise to such high value that it would not be effective to drop the relay armature but would prevent the raising of the armature if it once dropped.

In view of the hereinbefore stated considerations applicant has for a main object the provision of means to most certainly insure the dropping of a track circuit relay

armature upon the entrance of a train to the section to which the relay is connected.

Another object of applicant's invention is to provide means for actually breaking the circuit of a track circuit relay upon the 60 entrance of a train to the section to which the relay is connected.

A further object of applicant's invention is to retain every advantage of the present track circuit arrangement in connection 65 with his new arrangement.

Other objects and advantages will appear as the description of the particular physical embodiment selected to illustrate the invention progresses, and the novel feature of the 70 invention will be particularly pointed out in the appended claims.

In describing the invention in detail, and the particular physical embodiment selected to illustrate the invention, reference is had 75 to the accompanying drawing, wherein I have illustrated a particular preferred physical embodiment of my invention, and wherein like characters of reference designate corresponding parts throughout the 80 several views, and in which:

Figure 1 is a schematic representation of a well known track circuit with my invention applied thereto; Fig. 2, is a sectional view illustrating a conventional track instrument usable with my invention.

In Fig. 1, numeral 1 indicates one rail of a trackway and 2 the other rail. The track circuit section is set off from the rest of the trackway by insulating joints, 3, 4, 5 and 6. At one end the battery 7 is connected across the rails and at the other end the relay 8 is connected across the rails. The signal 9 energized by battery 10 through a circuit 85 passing through armature 11 controls traffic over the section. All of this construction is old and well known and is representative of standard practice with end fed direct current track circuits, which has been selected as most simple to illustrate the invention, 100 although applicant does not mean to exclude the use of his invention with alternating current track circuits, or center or offset feed, as it is usable with any of the commercial standard track circuits, whether the relay derives its entire energy from the track 105 rails or not.

In Fig. 1 it will be seen that battery 7 is connected to the rails by two leads, 12 and 13 and that 13 goes through a diagrammati- 110

cally indicated device 14 and emerges as 15. In the same way relay 8 is connected to the rails by leads 16 and 17 and that 17 passes through a similar device 14 and emerges as 18. The insertion of these devices 14 in the leads 13 and 17 is the way in which applicant expresses the idea of his invention.

The device designated as a whole by 14 is conventionally illustrated by Fig. 2. The device 14 is old and well known and exists in many forms, but as no particular form is essential to the expression of applicant's invention, a conventional form merely has been illustrated. This device 14 is known as a track instrument and is merely a means whereby a passing train may by mechanical action cause a change in a circuit. In the form shown the device consists of a lever 19 suitably pivoted, as to a tie 20, by pin 21 and the lever by end 22 bears against rail 1. As is well understood by those skilled in railway track work, when a train passes over the rail 1 there is relative movement between the tie 20 and the rail 1. This movement results in depressing end 22 and raising end 23. End 23 is connected, as by link 24 to a conducting member 25 which bridges terminals 26 and 27. When end 23 rises, bridge 25 rises and disconnects 26 and 27 and so lead 15 and lead 13, insulation being placed at proper points as 28, 29, 30, 31 and 32 to prevent undesired electrical paths.

The operation of the device is quite obvious. A train entering the section in the direction of traffic, as shown by the arrow A, would operate track instrument 14 at the signal 9 and break the circuit through 17 and 18 and so the source of potential would be entirely cut off from the relay 8, so that the armature would have to drop regardless of the value in ohms of the shunt formed by the wheels and axles. In short there is an absolute break in the circuit, so that the means used to drop the relay armature is absolute and positive and not marginal.

Applicant has also shown a track instrument 14 inserted in one of the leads of battery 7. This may or may not be done. If there is no necessity for movement against the normal direction of traffic this may be dispensed with but for complete protection it should be used because at times trains may enter the section from the end at which the source of potential is positioned.

It is to be observed that although applicant has introduced into the ordinary and well known track circuit, another element, nevertheless, the track circuit may function just as it now does if the added element fails to operate. The shunt now depended upon to deenergize a track relay is just as

effective in applicant's arrangement as in any track circuit. If applicant's added element becomes deranged so that the circuit is broken therethrough improperly then the failure is on the side of safety as the signal would be placed at danger position thereby.

Although I have particularly described the construction of one physical embodiment of my invention, and explained the operation and principle thereof, nevertheless, I desire to have it understood that the form selected is merely illustrative, but does not exhaust the possible physical embodiments of the idea of means underlying my invention.

What I claim as new and desire to secure by Letters Patent of the United States, is:

1. In a track circuit, in combination: rails; a source of potential connected across the rails at one point, a relay connected across the rails at another point and means operable mechanically by a passing train inserted in a connection of the relay for breaking the circuit thereof.

2. In a track circuit, in combination: rails; a source of potential connected across the rails at one point; a relay connected across the rails at another point and means including a circuit controller operable mechanically by a passing train inserted in a connection of the relay.

3. In a track circuit, in combination: rails; a source of potential connected across the rails at one point; a relay connected across the rails at another point and means associated with the rail adjacent the relay operable by a passing train for breaking the relay circuit.

4. In a track circuit, in combination: rails; a source of potential connected across the rails at one point; a relay connected across the rails at another point and means operable mechanically by a passing train for breaking the source of potential circuit.

5. In a track circuit, in combination: rails; a source of potential connected across the rails at one point; a relay connected across the rails at another point and means operable by a passing train for breaking the relay circuit and means operable by a passing train for breaking the source of potential circuit.

6. In a track circuit, in combination: rails; a source of potential connected across the rails at one point; a relay connected across the rails at another point whereby a passing train will shunt the relay and means whereby the relay circuit will be broken even if it is or is not properly shunted by a train spanning the rails at its point of connection.

WILLIAM H. B. LAVARACK.
